Primary Examiner — Karen S Acker*Assistant Examiner* — Wendy Arminio*74) Attorney, Agent, or Firm* — Leong C. Lei(57) **CLAIM**

The ornamental design for an inflatable packing material, as shown and described.

DESCRIPTION

FIG. 1 is a perspective view of an inflatable packing material showing my present design shown in an inflated condition; FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a deflated top view of FIG. 6 thereof; and,

FIG. 9 is a deflated perspective view of FIG. 1 thereof.
